UNITED STATES PATENT OFFICE.

JAMES T. FORD, OF CARTAGENA, COLOMBIA.

METHOD OF BUILDING SUBAQUEOUS FOUNDATIONS.

SPECIFICATION forming part of Letters Patent No. 707,093, dated August 19, 1902.

Application filed April 10, 1902. Serial No. 102,280. (No model.)

To all whom it may concern:

Be it known that I, JAMES T. FORD, a resident of Cartagena, Colombia, have invented certain new and useful Improvements in 5 Methods of Building Subaqueous Foundations; and I do hereby declare the following to be a full, clear, and exact description of the invention, such as will enable others skilled in the art to which it appertains to make and to use the same.

My invention relates to an improved method of building subaqueous or submarine foundations, the primary object of the invention being to provide a method whereby foundations 15 can be constructed upon the bed-rock of waterways, which has heretofore been utterly impossible by the aid of known methods, and, further, to vastly cheapen the construction of submarine foundations even though 20 the conditions be such as to make it possible for building by known methods.

Heretofore in the construction of foundations for dams, bridge-piers, &c., on strata of rock that underlie more or less porous 25 earths, with water on top in beds of rivers and the like, it has been the practice to construct coffer-dams in the water at first and work downward by ordinary excavation to such depth as may be possible for the coffer-dam; 30 but as the depth increases it becomes necessary to keep the water out by other means than pumping, and an air-tight caisson of wood or metal is used and kept free of water by air-pressure, as is well understood. As 35 the caisson is moved downward a greater air-pressure is needed to keep out the water. This air-pressure is extremely injurious to the workmen, resulting in what is known as the "caisson disease" and usually greatly 40 shortening the lives of those engaged in such work. Beyond a certain depth, which it is safe to say is one hundred and twenty feet, the caisson cannot be used, for the reason that such enormous air-pressure, which would 45 be nearly four atmospheres, is required to keep out the water that workmen cannot live therein, and hence where it is necessary to build foundations more than one hundred and twenty feet below water-level such work 50 has been deemed impossible and abandoned, and even where it has not been necessary to go below this depth the work has been aban-

doned owing to the great expense of constructing the foundations with the caisson; and while my improved method will not entirely dispense with the use of the caisson and other known methods it will dispense with their use at extremely dangerous and costly depths, or, in other words, will build the foundation up from bed-rock to a point 60 where the caisson and other known methods can be employed without inordinate expense and reduce the danger to which the workmen are subjected to the minimum.

With these objects in view the invention 65 consists in certain novel steps of the method which will be more fully hereinafter explained, and pointed out in the claims.

In the accompanying drawings, Figure 1 is a view illustrating a section taken through 70 a river and bed and showing my improved method carried out. Fig. 2 is a view in section on the line $x-x$ of Fig. 1, and Fig. 3 is a view of a partially-completed tunnel.

1 represents the water of a river, 2, 3, 4, 75 and 5 underlying strata of earth more or less impervious to water, and 6 the bed-rock, which for the purpose of illustrating my invention is shown with a surface of rather extreme unevenness.

80 In carrying out my improved method the first step is to sink shafts 7 and 8, respectively, on opposite sides of the stream and as near thereto as is safe from floods and the like and directly in the alignment of the proposed work. These shafts are carried down to bed-rock 6, which we will suppose is one hundred and fifty feet below water-level, which would be of sufficient depth to make all known methods practically worthless and with which 90 the foundations could not be built. At the bottom of both shafts the workmen now begin to tunnel toward the center of the river-bed, following the course of the bed-rock, filling in the uneven surface with cement. 95 As the tunnel progresses it is braced by timbers 9 and the walls cemented. For instance, for the purpose of illustration we will say that we dig a tunnel twenty feet in diameter and line the same with a cement 100 wall 10—say seven feet thick—thus leaving an arched opening of six feet in width large enough to permit the removal of the excavation. I preferably leave a space at the

top sufficiently large to enable the workmen to ram or pack the cement, and the top timbers can be used as side timbers for the tunnel next above, as will be hereinafter explained. If the bed-rock takes a sudden depression, as shown at 11 in the drawings, the workmen will dig down to a comparatively lower plane and tunnel as before, when a second tunnel can be built on top of this lower tunnel, as clearly shown at 12. When a comparatively level foundation is thus formed from one shaft to the other, another tunnel 13 is built on top of the first, and so on until the foundation rises to the desired height or until a stratum is reached which is pervious to water, permitting a too great quantity to pass therethrough to be removed by pumps and other known methods. When such a contingency arises, the foundation will be necessarily of a height which will permit the remaining portion to be built with the aid of the caisson or other known methods without undue expense and danger.

If desired, the tunnels can be left open, thus leaving the foundation for all time open for inspection, or, if preferred, the tunnels may be filled in solid after completion.

While it might at first appear to the untutored mind that my improved method might be impracticable by reason of the uncertainty of the condition of the various strata of earth which might be encountered, still every careful engineer by the aid of numerous borings should know the precise condition and location of all strata which will be encountered, and he can thereby avoid any danger of encountering a condition which would make it impossible to keep out or remove the water which might, owing to the peculiar formation of earth strata, flow too rapidly into the excavation. This, however, is a condition of affairs which rarely exists as far below the river-bottom as my construction of tunneling would begin and at any event could only result in compelling the engineer to select another site for the foundation.

My improved method embodies four distinct features of advantage: First, and most important, it enables submarine foundations to be built which by any before-known method were impossible; second, foundations can be cheaper and better built in locations which might be built by known methods; third, the foundation can be constructed according to my method which will always be open to inspection, and, fourth, the river and strata immediately underlying the same are not disturbed until the foundation is almost completed, as the foundation begins at bed-rock and grows upward to a point where the remaining portion can be completed in a com-

paratively short time, thus avoiding all flood or storm damage during the protracted period of construction of such work under present methods where very costly precautions are necessary to prevent accident.

I would of course have it understood that I do not wish to be limited to the number of tunnels side by side nor on top of each other nor use of cement walls as a foundation, as I might use walls of stone, brick, or other material; nor is the precise shape of the tunnels essential, as they can be varied at will and according to the varying conditions which may be met with.

Having fully described my invention, what I claim as new, and desire to secure by Letters Patent, is—

1. A method of constructing subaqueous foundations, consisting in first sinking a shaft, then tunneling beneath the water-bed, and then reinforcing said tunnel from within to convert it into a superstructure-supporting foundation.

2. A method of building subaqueous foundations consisting in first sinking a shaft beyond the water's edge and down to bed-rock, then excavating along bed-rock, walling said excavation, excavating on top of said foundation thus formed, and walling said second excavation.

3. A method of constructing subaqueous foundations consisting in first sinking shafts on opposite sides of the water's edge, down to bed-rock, then tunneling along bed-rock from shaft to shaft walling or lining the tunnel as it is dug, then building another tunnel on top of the first and soon up to the desired height.

4. A method of constructing subaqueous foundations consisting in first sinking shafts on opposite sides of the water a safe distance from the water's edge and down to bed-rock, then tunneling along bed-rock from shaft to shaft cementing the tunnel-walls to the desired thickness, and then building tunnel on tunnel until the desired height is reached.

5. A method of constructing subaqueous foundations consisting in sinking one or more shafts to the desired depth, then tunneling from said shaft or shafts beneath the water-bed to the desired length for the foundation, then walling, lining or filling said tunnel or tunnels, and then erecting the dam or other structure on said tunnel or tunnels.

In testimony whereof I have signed this specification in the presence of two subscribing witnesses.

JAMES T. FORD.
